Wiltie I. Gladfelter and Carl C. H. Hauger, Philadelphia, Pa., assignors to Crown Cork & Seal Company, Inc., Baltimore, Md., a corporation of New York

Application June 26, 1940, Serial No. 342,568

15 Claims. (Cl. 101—40)

The present invention relates to a machine for printing upon curved surfaces, such as circular cylindrical surfaces. In the specific embodiments shown herein, the machine is adapted for printing upon the surfaces of containers, such as sheet metal cans and the like, but, of course, the invention is not limited to such use, as it may readily be adapted for printing the surfaces of a wide variety of different classes of articles, such as bottles, jars, tumblers, paper or cardboard cartons or tubes, collapsible lead tubes, and the like.

It is an object of the invention to provide a high speed machine for printing, preferably with a plurality of colors, on the curved surfaces of such articles as sheet metal cans after the same have been formed to cylindrical shape, and to perform the printing operation at such a rate of speed as to keep pace with a commercial can fabricating line.

Heretofore, in the can art, can bodies have universally been decorated, if at all, by printing sheet metal sheets in flat condition, prior to cutting the sheets into blanks and forming the blanks into can bodies in a standard body maker, wherein the blanks are wrapped around a horn and the edges secured together, for instance, by a double lock, soldered side seam. Certain disadvantages are inherent in that procedure, however, since the blank folding wings in the body maker are likely to scratch or mar the previously applied printing, or the decoration is likely to become damaged during subsequent operations, such as when the end members are seamed-on, when the interior is coated, or when the cans are tested for leaks.

It is an object of the present invention to apply the decoration to the surface of the can as substantially the last step in its manufacture, or, at least, after all of the operations have been performed which might damage the decoration on the exterior surface of the can body.

With the recent advent of relatively tall, drawn, seamless can bodies, such as are made in accordance with the applications of Calleson et al., Serial Nos. 129,068 and 280,650, filed, respectively, March 4, 1937 and June 2, 1939, special problems as to decorating the cans arose, since the sheet metal from which the can bodies are made could not be lithographed or decorated in the flat. The drawing operations obviously would entirely destroy any decoration previously applied to the flat blanks.

Although not confined thereto, the machine of the present invention is particularly adapted for

printing the cylindrical surface of deep drawn, seamless containers, of the type shown in the applications of Calleson et al., Serial Nos. 129,068 and 280,650, filed, respectively, March 4, 1937 and June 2, 1939.

It is an object of the invention to provide a machine which will take the containers in a line, after they have been fabricated, and preferably after they have been coated externally with a base coat, such as a baked aluminum lacquer, and apply to the cylindrical surface thereof, a printed decoration in a plurality of colors, and then discharge the printed cans at the same speed, without marring their printed surfaces.

It is a further object of the invention to provide novel can-handling instrumentalities in the machine, whereby the cans are supported for rotation by their ends.

A further object of the invention is to provide, in combination with means for conveying the cans along a predetermined path, supported for free rotation, as aforesaid, novel printing transfer means adapted to make rolling contact successively with the individual cans.

A further object is to provide, in combination, a novel can-supporting turret, novel transfer blanket means cooperating therewith, and a plurality of individual printing assemblies adapted to apply to the transfer blanket means, a plurality of differently colored ink patterns.

It is a further object of the invention to provide, in an apparatus of the class described, a turret for rotatably supporting a plurality of cans and a transfer cylinder rotating in timed relation therewith and having a pair of diametrically spaced transfer blankets associated therewith, each adapted to print upon alternate cans in the turret, whereby the production rate of the machine is substantially doubled.

It is a further object of the invention to provide novel printing assemblies adapted to cooperate with a transfer cylinder and including improved, adjustable ink applying means for the plate cylinder or roll.

A further object of the invention is to provide a machine that may be employed to apply to the cylindrical surfaces of containers or the like, a continuous coating of ink or other coating material in a plurality of layers, or, if desired, to apply a plurality of differently colored continuous bands to such surfaces.

Other and further objects and advantages of the present invention will be apparent to one skilled in the art from a consideration of the specific embodiments disclosed in the accom-

panying drawings and described below. It must be understood, however, that the drawings and the following description are illustrative only and are in no sense restrictive of the invention, since many modifications will readily occur to one skilled in the art after a consideration of this disclosure.

Figure 32 is a diagrammatic view, partly in vertical section and partially in side elevation, showing a further modification of the invention in which the machine applies a plurality of continuous coatings for continuous bands to the containers.

General organization and driving means

Referring to Figure 1, the machine of the present invention comprises, generally, a rotatable can turret 12 having chuck assemblies 13 supported thereon and adapted to receive containers 11 in a line rolling down an infeed conveyor 10. A rotatable transfer cylinder 14 has a pair of diametrically opposed transfer blankets 15, 16 on its periphery, each positioned to make rolling contact with alternate cans in the turret. A plurality of printing assemblies 17, 18, 19, 20 are positioned about the transfer cylinder, to apply ink or other coating material in a plurality of different colors, in pattern form, to the transfer blankets. After the cans have been subjected to rolling contact with one transfer blanket or the other and have received printing therefrom, they are discharged by the chucks and received in special holding brackets 21, mounted upon an outfeed conveyor chain 22, which uprights the containers and delivers them to conveying means, not shown, which may carry them to a baking oven or the like.

As indicated in Figure 3, the main driving pinion 23 for the machine is driven by an electric motor 25, operating through a speed reducer 26 and a belt 27, trained about pulleys 28, 29. Referring to Figure 4, the main driving pinion 23 is keyed upon a shaft 30, journaled in the main frame casting 31 of the machine. At its end opposite to the end carrying the pulley 29, the shaft 30 has a pinion 32, adapted to be enmeshed with a pinion 33 secured to the end of a longitudinally movable shaft 34, journaled in collars 35 on a bracket 36 and having a hand wheel 37 pinned thereon. A coil compression spring 38 normally urges the shaft and pinion 33 forwardly, out of mesh with the pinion 32, but, when it is desired to turn the machine over by hand, the shaft may be forced inwardly against the compression of the spring.

The main driving pinion 23 is in mesh with a large gear 40, keyed to a main transverse shaft 41, journaled by appropriate bearings 42 in the frame 31, and carrying at its forward end the transfer cylinder 14. The hub of the large gear 40 carries a smaller pinion 43, in mesh with a large gear 44, keyed to a second main transverse shaft 45 (Fig. 6) journaled in bearings 46 secured to one end 47 of the frame 31. The shaft 45 carries, at its front end, the can-holding turret 12 and, in the embodiment illustrated, the speed ratio between the transfer cylinder and the can-holding turret is six to one, since there are twelve can-holding chucks on the turret and two transfer blankets 15, 16 on the transfer cylinder 14.

The gear 49 is in mesh with a plurality of pinions 48, 49, 50, 51, each associated with one of the printing assemblies 17—20, as hereinafter explained. The shaft 41 at its rear end carries a cam plate 52, having cam grooves in its opposite faces, adapted to actuate links 53, 54, respectively, which impart certain motions at predetermined times to ductor rolls and fountain

rolls associated with the printing assemblies, as explained below.

The turret supporting shaft 45 carries an additional gear 55, in mesh with a spur gear 56, fixed to the shaft 51 which carries the sprocket 53 and the outfeed conveyor chain 22.

The can turret and chuck assemblies

As pointed out above, the cans 11, rolling down the infeed chute 10, are received in chuck assemblies 13 (twelve in number) carried by the turret 12, which rotates about the axis of the horizontal transverse shaft 45. As shown in Figures 5 and 7, the turret 12 comprises a central hub 60 and a pair of spaced, radially projecting webs or heads 61, 62 projecting therefrom and interconnected by a plurality of longitudinally extending flanges 63. The heads 61, 62 project outwardly beyond the webs 63 and are provided with a plurality of sets of parallel reinforcing ribs 64, 65 defining ways 66, 67, in which the chuck assemblies hereinafter mentioned are mounted. The ways or openings therebetween in the head 62 are aligned with similar ways 66', 67' formed in the head 61.

Each chuck assembly comprises a pair of brackets or cradles 68, 68' (Fig. 12) slidably mounted for radial movement in the aligned openings between pairs of ways 66, 67, 66', 67'. Each cradle mounted in the outer head 62 comprises a central block portion disposed between the ways 66, 67, a forwardly projecting portion 69, having a radially outwardly turned end 70 and an intermediate hollow boss 71 adapted to house bearing means 72 for a spindle 73, the spindle also being journalled in bearings 74, carried by an outwardly projecting portion 75 of the central block. On the rear face of the block portion of the cradle, there is bolted, or otherwise secured, a rearwardly projecting pocket-forming bracket 76, having a concave central portion adapted to receive a can and laterally projecting portions 77 (Fig. 14) which terminate in substantially abutting relation with similar portions of the next pocket-forming bracket in the next opening in the head 62.

The other head 61 carries a plurality of similar assemblies, disposed in substantially the opposite relation. That is, each cradle member 68' comprises a rearwardly projecting portion 69', an upturned end 70', bosses 71', 75' carrying bearings 72', 74' with a spindle 73' journalled therein. The front face of each cradle 68' carries a forwardly projecting, pocket-forming bracket 76', having a central concave portion adapted to receive one end of a can, and laterally projecting wing portions 77' disposed in substantially abutting relation with corresponding elements on the adjacent members. Thus, the pocket-forming brackets 76, 76' provide peripherally disposed pockets on the turret, into which the cans fall by gravity from the infeed conveyor 10 as the turret rotates in a clockwise direction. Figure 1.

The spindles 73, 73', journalled in the bearings 72, 72', 74, 74', are mounted for axial movement with respect thereto and relative to centrally disposed plugs 80, 80', bearing against thrust bearings 81, 81' at one end and having coil compression springs 82, 82' interposed between their other ends and the hollow interior of the spindles 73, 73'. Hence, the springs 82, 82' at all times urge the spindles toward the can supported in the adjacent pocket, movement in that direction being permitted by the relative sliding movement between the spindles and the

internal plugs 80, 80'. Rollers 85, 85' having peripheral grooves 86, 86', are secured to the spindles 73, 73' by diametric pins 87, 87', disposed in axial slots 88, 88' in the internal plugs 80, 80'. Forked levers 90, 90' (Figs. 12 and 16), pivoted to the members 69, 69' are provided at one end with cam following rolls 91, 91' and at their other bifurcated ends 92, 92' with rollers 93, 93' disposed in the grooves in the roller 85, 85'. Stationary cam rings 95, 95', fixed, respectively, to a stationary bracket 96 and to the machine frame, have laterally projecting portions positioned to be engaged by the rollers 91, 91' to swing the levers and thereby move the rollers 85, 85' and the spindles 73, 73' away from the ends of the can in the pocket, against the compression of the springs 82, 82', such movement being permitted by reason of the fact that the connecting pins 87, 87' ride in elongated slots 88, 88' in the central plugs 80, 80'.

The spindle 73 is provided at its can-engaging end with an enlarged head 97 having a cylindrical peripheral surface 98 of a radius equal to the can radius, and a concave, central recess 99, adapted to engage the neck end of a can. The spindle head 97', instead of being provided with a central recess, has a forwardly projecting plug portion 99', adapted to engage the can at the bottom end thereof. Of course, this member may be given any desired shape, corresponding to the shape of the bottom end of the container or other article to be supported. In the embodiment shown, the container 11 has a concave bottom end member double-seamed thereto, thereby providing a concave lower end, defined by a bead 11a, similar to a standard sanitary seam.

As pointed out above, the cam 95 is carried by a bracket 96 (Fig. 1) having a bearing 105 for the end of the shaft 45 and upwardly and downwardly projecting arms 106, 107, bolted to the side face of the machine frame. The other cam track 95', however, is bolted directly to the machine housing or frame adjacent the intermediate bearing 108 and the shaft 45. As shown in Figure 5, the operative, projecting portions of the cams 95, 95' are disposed opposite each other, to withdraw the can end engaging members 97, 97' simultaneously, to permit a can to be discharged from the chuck and to make room for a new can to be received therein. When the cams 95, 95' release the rollers 91, 91', the springs 82, 82' force the can end engaging heads 97, 97' toward the can and, by engagement therewith, lift the can from its initial position resting in the pockets 76, 76'. When so raised and engaged by the ends of the spindles, the cans are supported for free rotation.

Such rotation is imparted to the spindles and to the can by the transfer cylinder 14, described below, which is provided with tracks 110, 111, 110', 111', disposed to make driving contact with the peripheries of the rollers 85, 85' and heads 97, 97'. As previously pointed out, the cylindrical surfaces of the rollers and heads are struck about centers disposed coaxially with the can on radii equal to the can. Hence, the cylindrical surface of the can is rotated at the same peripheral speed as the rollers 85, 85' and heads 97, 97'. As pointed out below, the printing blankets on the periphery of the transfer cylinder are disposed on a cylindrical surface which is a projection of the surfaces of the tracks 110, 111, 110', 111' on the transfer cylinder.

As the can-holding turret is rotated, the chuck assemblies thereon are brought successively into

a position adjacent the path of movement of the transfer blankets 15, 16 on the transfer cylinder or turret 14. During the continuation of their movement, the chuck assemblies and the cans held therein follow a path coinciding with the peripheries and the path of movement of the printing blankets, concentric to the axis of the shaft 41 and on an arc intersecting the normal path of movement of the chucks and cans. Hence, the chucks and the cans must move radially inwardly relative to the turret 12 during their engagement with the transfer blankets. This radial movement is permitted by reason of the fact that the cradles 68, 68' are slidably supported in the spaces defined by the radial ways 66, 67, 66', 67'. As indicated in Figures 5, 12 and 15, springs 115, 115' urge the brackets radially outwardly at all times, movement in that direction being limited by caps 116, 116', secured by appropriate bolts or the like to the ends of the ribs 64, 65, 64', 65'. The central blocks of the cradles 68, 68' may be provided with lubricant-receiving grooves 117, as indicated in Figure 17, to lubricate the bearing surfaces between the blocks and the ways.

The radial inward movement of the chuck assemblies and the cans is relatively slight, since the extent of travel of the cans on an arc concentric to the center of the shaft 41 is quite short, and, in the embodiment illustrated, in the neighborhood of 15°.

The transfer cylinder

As explained above, the transfer cylinder 14 is mounted on the shaft 41 and, in the embodiment illustrated, is rotated six times as fast as the can supporting turret, by means of the intermeshing gears 43, 44. Referring to Figure 4, the cylinder comprises a central hub 120 having a tapered bore keyed to the tapered end of the shaft 41. A drum casting 121, bolted to the hub, has oppositely projecting portions 122, 123, provided with peripheral surfaces 124, 125 which extend throughout substantially a quadrant, concentric to the axis of the shaft 41. The laterally projecting portions also carry forwardly and rearwardly projecting flanges 126, 127, 128, 129, reference being had to Figures 4, 7 and 12. These flanges serve as supporting means for the tracks 110, 111, 110', 111', previously described, which impart rotation to the can-supporting cylinders associated with the chuck assemblies.

The transfer blankets 15, 16 are supported by the peripheral quadrants 124, 125, with cushioning pads 130 of cloth or the like positioned therebelow. The parallel webs 122, 123 of the transfer cylinder or drum carry four pairs of plates 131, 131' (Figs. 4, 7, 8 and 26) in which shafts 132 for the printing blanket and shafts 133 for the cushion pads are journaled. The shafts have squared ends for engagement by a wrench and carry ratchets 134, which are engaged by spring-pressed pawls 135. Hence, the tension applied to the pads and the rubber transfer blankets may be accurately determined and, when desired, the position of the effective surfaces of the blankets may be adjusted.

As the transfer cylinder rotates, the transfer blankets are revolved past the cans supported for rotation in the chuck assemblies. Each blanket makes rolling contact with alternate cans on the turret and transfers a printed impression upon the cylindrical surface thereof. The effective length of each blanket corresponds to substantially the entire periphery of a can. Rota-

tional movement is imparted to the can-holding spindles and the cans primarily by the driving relation between the tracks 110, 111, 110', 111' carried by the transfer cylinder, and not by a driving engagement between the transfer blankets and the can bodies. Hence, no smearing occurs between the blankets and the cans.

After transferring a printed pattern to a can, each transfer blanket makes rolling contact with 10 the plate cylinders or rolls of the printing assemblies 17, 18, 19 and 20, in the order named, reference being had to Figure 1, whereupon the blankets are provided with a new supply of ink, preferably in a plurality of different colors, in pattern form, to be transferred to a new can as the 15 rotation of the transfer cylinder continues.

The printing assemblies

The several printing assemblies 17, 18, 19 and 20 are carried by laterally and upwardly projecting flanges 140, 141 associated with the main frame. The spaced front and rear walls 142, 143 of the main frame (Fig. 4) are integrally connected to transversely extending sleeves 144, 145, 146, 147, each sleeve being provided with a laterally projecting flattened seat 148 at its rear end, to which a roll carrying bracket 149 is attached.

As shown in Figures 4, 6 and 22, each cylindrical sleeve of the frame carries an eccentric bushing 150 in which a shaft 151 is journaled in appropriate bearings 152, 153. This shaft at its forward, conical end 154 carries a plate roll 155 and at its rear end is provided with a pinion, such as that shown at 50 in Figure 4, in mesh with the large gear 40 on the shaft 41 carrying the transfer cylinder 14. The gear ratio between the gear 40 and the gears 48—51 is such that each plate roll 155 rotates at the same peripheral speed as the transfer cylinder.

Each roll-supporting bracket 149 is provided with an upstanding boss in which a stub shaft 157 is bolted, and a spur gear 158 is journaled thereon, positioned in mesh with a gear 48—51. Each bracket 149 has a second outwardly projecting boss 159 associated therewith in which a shaft 160 is journaled, the latter having a gear 161 on its rear end in mesh with the gear 158, and having an ink cylinder 162 at its forward end. Thus, rotation is imparted to the plate 50 roll and the inking cylinder by the gears 40, 49, 158 and 161.

The ink cylinder 162, in accordance with conventional practice, is preferably covered with a rubber composition. In Figures 20, 24 and 25, a novel form of cylinder is shown which effectively prevents overheating of the roll and the covering during continuous operation. The central hub 163 has a plurality of outwardly projecting spirally disposed ribs 164 formed integrally therewith. In assembling the parts, the cylindrical element 162 may be heated and shrunk upon the outer edges of the spiral ribs. Thus, when the roll rotates, an endwise circulation of air is set up through the roll interior, to carry off excessive heat and to prevent deterioration of the rubber covering.

Bolted to the front face of the main frame portion 141 (Fig. 1) are a plurality of brackets 165, having ink reservoirs 166 on their upper surfaces and bearings 167 for the shafts 160 carried by the ends of spaced laterally projecting parallel arms. As shown in Figure 20, each reservoir 166 has a fountain roll 168 associated with its open side 169, the fountain roll being 75 given a step by step, intermittent rotation by

means described below. A ductor roll 170 is mounted on a shaft 170' journalled in the ends of levers 171, fixed to a rock shaft 172 oscillated by means hereinafter described, to cause the ductor roll to swing back and forth from a position in contact with the fountain roll 168 to a position contacting the ink cylinder 162.

A pair of form rolls 175, 176 are carried by shafts 177, 178, journalled in bearings which are mounted in eccentric sleeves 183 in the lower ends of levers 179, 180, pivotally carried by the shaft 160. The form rolls 175, 176 thus may be accurately adjusted to contact the surfaces of the ink cylinder or form cylinder 162 and the plate roll 155. Major adjustments of the arms 179, 180 are effected by bolts 181 disposed in slots 182 in the arm, while minor adjustments may be effected by eccentrics 183.

Each printing assembly also includes a pair of longitudinally reciprocable distributor rolls 185, 186 in contact with the ink cylinder or form cylinder 162. As indicated in Figure 20, these rolls are fixed upon shafts 187 mounted in bearing blocks 188 disposed in slots 189, so that their position relative to the form cylinder 162 may be accurately adjusted. Longitudinal reciprocating movement is imparted to the rolls by levers 190, 191 (Fig. 8) having cam following rollers 192 disposed in a cam groove 193 mounted on the outer end of the form cylinder supporting shaft 160, the levers being pivoted at 194 and having their opposite ends 195 operatively connected to the shafts 187, thereby to impart longitudinal reciprocations to the distributor rolls as the form cylinder rotates.

As indicated in Figure 20, each ink reservoir 166 preferably is provided with means for accurately controlling the thickness of the film of ink applied to the fountain roll 168. Preferably, this means takes the form of a false bottom member 196 having a downwardly inclined upper surface 197 terminating in a free edge 198 projecting through the open side 169 into proximity to the roll 168. The degree of projection of the free end 198 may be accurately adjusted by bolts 199 extending through the rear wall of the reservoir and threaded to the rear wall of the false bottom member. A bolt 200 extending through a slide in the bottom of the reservoir may be provided to maintain the false bottom 197 in accurately adjusted position.

Actuating mechanism for fountain rolls and ductor rolls

As pointed out above, the cam plate 52, fast on the transfer cylinder shaft 41, has one cam groove 201 on its rear face and another, similar groove 202 on its front face. Rods 53, 54 are provided at their lower ends with bifurcated portions 203, 204, straddling the extensions 205 of the hub of the cam 52, and, at intermediate portions, with cam following rolls 206, 207 disposed in the grooves 202, 201, respectively. Hence, as the shaft 41 and cam 52 rotate, the rods 53, 54 are reciprocated.

Referring to Figure 6, it will be seen that the rod 53 actuates an appropriate linkage system, to impart intermittent rotation to the several fountain rolls. At its upper end, the rod 53 is connected to a crank arm 208, fixed to a transverse rock shaft 209 journalled in a bracket 209' and in the frame flange 140 and having at an intermediate point a crank arm 210, which is connected to laterally projecting links 211, 212. Each fountain roll shaft 213, 214, 215, 216, jour-

naled in bearings carried by the parallel arms of one of the brackets 165, has at its rear end an oscillating bracket 217 carrying a pawl 219 urged by a spring 218 into engagement with a ratchet 220 fast on the fountain roll shaft. The links 211, 212 are connected to the pawl carrying levers 217 associated with the fountain roll shafts 214, 215, respectively. A third link 221 is connected to the end of the link 212 and is connected at its other end to the pawl carrying lever 217 associated with the fountain roll shaft 216. Another link 222, connected to the lever 217 associated with the fountain roll shaft 213, derives motion from the link 211, an arm 217' rigidly connected to the pawl carrying lever on the shaft 214. Thus, as the rod 53 reciprocates, translational movement is imparted in opposite directions to the links 211, 212, 221, 222, which, in turn, oscillate the several pawl carrying levers 217 to impart step by step movement to the ratchets and the fountain rolls.

The rod 54, reciprocated by the roller 207 disposed in the cam groove 202, imparts oscillating, translational movement to the several ductor rolls. At its upper end, (Fig. 4a) the rod 54 is connected to a bifurcated crank 225 fast on a shaft 226 journalled at its rear end in a bearing in the bracket 209' and at its forward end in the frame flange 140 and having a crank arm 227 at an intermediate point which is connected to laterally projecting links 228, 229. The link 229 (Fig. 6) is connected to a T-shaped lever 230 pivoted on a shaft 231 having one end secured in the frame flange 141 and the other secured by a suitable bracket, not shown. An adjustable link 232 is connected to one arm of the T-lever 230 at one of its ends, while its other, bifurcated end 233 is connected to a cross-pin 234 (Figs. 6 and 6a) disposed between opposed springs 234' in the hollow head 235 of a lever 236, rigidly connected to the shaft 172 which carries the rock arms 171 in which the shaft 170' for the ductor roll 170 is journalled.

The third arm of the T-shaped lever 230 is connected to one end of a link 237, the other end of which is bifurcated as at 238 and connected to a cross-pin 234, disposed between opposed springs in a second hollow head 235 similar to that previously described and forming a part of a lever 236, connected to another rock shaft which supports the arms for the next ductor roll. Thus, the main link 229, which extends toward to the left in Figure 6, controls the oscillating movements of the ductor rolls of the two printing assemblies at the left of the machine. Similarly, the link 228, which projects toward the right, controls the movements of the ductor rolls of the printing assemblies at the right-hand end of the machine. The link 228 has a bifurcated end 240, connected to a transverse pin 241 disposed in a third shock-absorbing head 235, as previously described, the lever arm 236 thereof being connected to the rock shaft 172 of the adjacent printing assembly.

From the spring-pressed, cushion pin 241, another link 242 projects toward the right and is connected to one arm of a bell crank 243, pivoted on a shaft carried by the frame flange 140. The other arm of the bell crank is, in turn, connected to a link 244 having a bifurcated end 245, connected to a transverse pin 246, mounted between opposed springs in the head 235 of the fourth rock shaft actuating lever 236, the latter serving to oscillate the ductor roll of the adja-

cent printing assembly. Thus, as the cam plate 52 rotates, the links 229, 232, 237, 228, 242 and 244, and the levers connected thereto, impart oscillatory, translational movements to the several ductor rolls 170, to cause the same to swing back and forth between the contact with the fountain rolls 168 and the ink cylinders 162. The ink thus transferred is evenly spread and distributed over the surfaces of the ink cylinders by the longitudinally reciprocating distributor rolls 185, 186. It is picked up by the form rolls 175, 176 and applied to the plate cylinders or rolls 155. The latter cylinders print predetermined patterns of ink upon the transfer blanket, which subsequently transfers the same to the containers.

The plate roll adjustments

As pointed out above, the plate roll 155 (Fig. 4) is mounted upon the tapering end 154 of shaft 155. The latter is journalled in bearings 152, 153 mounted in the eccentric sleeve 150, the inner bearing races being spaced apart by a tube or sleeve 153' (Fig. 22). Hence, upon rotation of the eccentric sleeve 150, the shaft 151 and the plate roll 155 are moved relative to the transfer cylinder 14. As shown in Figures 4, 8 and 20, a ring 250, bolted to the forward end of the sleeve 150, is provided with a lateral extension 251, to which a block 252 is pivotally connected by a bolt 253. A pin 254, integral with the block 252, carries a collar 255 at its outer end, and a threaded sleeve 256 having a head 257 surrounds the pin 254 and is confined between the block 252 and the collar 255. The sleeve 256 extends through a threaded boss 258 mounted upon a pin 259 disposed in a hole in the face of the machine frame. A lock nut 259' bears against the face of the boss 258 to maintain the parts in adjusted position. Hence, by rotating the sleeve 256, the radial position of each plate roll 155 relative to the transfer blanket may be accurately determined.

Each plate roll 155 carries on its periphery a printing plate 260 which is adapted to print a pattern upon the transfer blanket. In the usual case, the plate on each roll is different from the plate on the next, since each plate prints a different pattern in ink of a different color. The various patterns applied to the transfer blanket must, of course, bear an extremely accurate predetermined relation with respect to each other. Hence, it is of importance that each printing plate be accurately adjusted circumferentially with respect to the printing blanket, for instance, to avoid overlapping or offsetting of the differently colored patterns applied to the blanket. In the present machine, this circumferential adjustment is effected by changing the circumferential position of the plate roll relative to its supporting shaft, the shaft being geared to the transfer cylinder shaft. The tapered end 154 of each plate roll shaft carries a radial plate 261, secured thereto by a bolt 262 and maintained in predetermined relation by pins 263 or the like. The plate 261 is provided with arcuate slots 264 (Fig. 8) through which guide pins 265, 266 project, the latter being screwed into threaded holes in the outer end face of the plate roll 155. The pin or bolt 266 is elongated and carries a block 267, pivoted thereto and provided with a pin extension 268 having a collar 269 secured to its other end. An externally threaded sleeve 270, having a head 271, surrounds the pin 268 and is confined between the block 267 and the collar 269. The

sleeve is threaded in a hollow, internally threaded boss 272 mounted on a post 273 secured in the end plate 261. If desired, a lock nut may be threaded on the sleeve 270 to prevent inadvertent rotation of the sleeve relative to the boss 272. By rotating the sleeve 270, the pin 268 and the block 267 are moved in one direction or another, thereby moving the roll 155 relative to the end plate 261 fast upon the end of the tapered portion 154 of the shaft 151. Hence, accurate circumferential adjustment between the shaft and plate roll may be effected.

The modified form of apparatus

15 In Figures 27-31, a somewhat modified form of apparatus is disclosed. This form differs from that previously described primarily in connection with the means for operating the can-holding chucks and in the cam actuating means for 20 rotating the fountain rolls and for oscillating the ductor rolls. The several printing assemblies 17', 18', 19', 20' may be substantially the same as those previously described. The transfer cylinder likewise substantially corresponds to that 25 shown in the first form, except that it is bolted to the hub 400 by bolts 401 disposed in arcuate slots 402, to permit angular adjustment relative to the shaft 41'. The transfer cylinder may have 30 blanket tightening and adjusting means similar to that shown in Figures 1 and 7 or the blankets may be secured to the outer ends of plates 403, pivoted at 404 and controlled by bolts 405, illustrated in Figure 27.

As shown in Figures 28, 30 and 31, the can-supporting chuck assemblies comprise cradles 410, 410' mounted for radial movement between ways 411, 412 formed in the two heads 413, 414 of the can-holding turret 415. Each cradle is urged outwardly by a spring 416, against an end 35 plate 417, connected across the ends of the ways. The blocks are provided with laterally projecting bracket portions 418, 419, the latter of which is shaped to provide a pocket for the end 11' of the can 11. The bracket portion 418 (Fig. 30) supports a lever 420 carrying at its outer, bifurcated end, roller 421 disposed in a groove 422 associated with the can end engaging spindle 423, journalled in bearings 424 in the cradle 410. The inner portion of the lever 420 carries a cam following roller 425 adapted to engage a cam track 426 carried by the stationary bearing sleeve 427 for the shaft 45' which carries the can turret. The lever 420 at its inner end is connected to a link 428 which extends forwardly and is connected to the inner end of a lever 429, carried adjacent the chuck assembly for supporting the front end of the can. As shown in Figures 28 and 31, the lever 429 is pivoted upon an outwardly projecting post 430, secured to the head 414 of the turret, and its radially outer end engages a lever 420', associated with the adjacent chuck assembly. The latter lever is pivoted to the forwardly extending bracket portion 418' of the radially slid able cradle 410', and its bifurcated end 421' carries rollers disposed in the groove of the can end spindle 423'. As a result of this construction, only one cam 426 is required to control the longitudinal movements of both can end engaging spindles. The movements imparted to the lever 420 which control the bottom end engaging member are transmitted by the link 428 and the lever 429 to the corresponding lever 421' at the other end of the chuck assembly.

In this modification, the transfer cylinder 14', adjacent each blank, carries only two can rotat-

ing tracks 435, 436, one being positioned to engage a cylindrical surface associated with each can end engaging spindle. In some cases, this is preferred, for the sake of simplicity, while, in other cases, the construction shown in Figure 12 is preferred, since the driving force is imparted to each spindle at opposite sides of the main spindle bearings and no tilting force is applied to the spindles.

Since the other details of the chuck assemblies are substantially the same as shown in Figure 12, they will not be described further.

The fountain roll and ductor roll actuating mechanism

A cam plate 201', secured to the rear end of the transfer cylinder shaft 41', supports a roller 206' carried by a rod 53' having a bifurcated lower end 203', straddling the shaft extension. At its upper end, the rod 53' is connected to a rock arm 208' on a rock shaft 209a which is connected by another arm 210' to the linkage system for rotating the several fountain rolls. The rod 53' is moved outwardly by the cam 201' and is retracted or moved inwardly by a compression spring 440 surrounding a rod 441 connected at 442 to the rod 53'. At its upper end, the spring 440 is disposed beneath a seat 443 carried by the bracket 209b, the rod 441 being guided in an appropriate aperture in the seat 443.

Similarly, the ductor roll actuating arm 54' has a lower bifurcated end 204' straddling the shaft extension and a roller 207' disposed upon a cam plate 202'. At its upper end, the rod 54' is connected to a rock arm 225' carried by a shaft 226' which transmits motion to the linkage system for the ductor roll oscillating devices. The rod 54' is moved outwardly by the cam plate 202' and is returned by a compression spring 445 surrounding a guide rod 446 connected at its lower end to a boss 447 carried by the rod 54' and at its upper end to a laterally projecting seat 448 formed adjacent the lower end of the bracket 209b.

The third modification

In Figure 32, there is disclosed somewhat diagrammatically, a form of apparatus adapted to apply to the cylindrical surfaces of containers or the like, a continuous coating of ink or coating material in a plurality of layers, or to apply to such surfaces a plurality of circumferentially continuous, differently colored bands. This form of the apparatus differs from the first form described above primarily in that a continuous rubber covered roll has been substituted for the transfer drum and the transfer blankets mounted thereon, and in that the intersecting arc between the path of movement of the containers and the transfer surface has been lengthened, for instance, by shortening the distance between the center of the turret and the transfer roll.

As shown in Figure 32, the hub 120a, mounted upon the shaft 41a carries a drum or roll 123a having a continuous periphery 500, carrying a rubber composition rim 501 which may be vulcanized or otherwise secured thereon. The several plate rolls 48a, 49a, 50a, 51a and the associated inking assemblies may be identical to those shown in the first form of the apparatus and described in detail above, with the exception that the rolls 49a-51a have circumferentially continuous surfaces and apply continuous layers of ink or coating material to the rubber surface 501 of the transfer roll.

The can holding chucks 13a are not shown in detail, since they may be substantially identical to those previously described. It should be noted, however, that the shaft 45a for the can holding turret 12a is nearer to the drum shaft 41a, or the drum or turret, or both, are of larger diameter, so that the containers and the chucks make a longer roller contact with the drum surface during revolution of the turret. To accommodate this longer movement, the chucks 13a have greater radial inward movement relative to the turret axis. This may be accomplished by lengthening the ways 66a, 67a in which the chucks are slidably mounted.

Instead of providing continuous surfaces on the plate rolls 49a-51a, the rolls may have raised bands thereon, appropriately staggered with respect to each other, and each roll, or certain of the rolls may apply continuous bands or stripes of differently colored inks to the rubber surface 501 of the transfer drum which, in turn, applies the ink in a corresponding pattern to the containers.

When a continuous coating of material is to be applied to the surfaces of the containers, it is desirable that the containers make between 2 and 4½ rotations while in rolling contact with the coating drum, in order that the line of commencement of coating may be substantially obliterated by the subsequent coatings applied. If only one layer of coating material is applied, the lap mark is very pronounced, but if three or four layers are rolled upon the surface, the difference between the portion coated three times and that having four layers is imperceptible. The number of rotations made by the containers is dependent, of course, upon the relative speed of rotation of the coating drum and the turret and upon the length of the arc of the coating roll followed by the containers in rolling contact therewith during their revolution with the turret.

Operation

It is thought that the mode of operation of the machines of the present invention will be apparent from a consideration of the foregoing description. Cans rolling down the infeed conveyor 10 under gravity are received in the pockets formed by the inwardly projecting brackets 76, 76' of the chuck assemblies 13, the can engaging heads 97, 97' being at that time retracted as shown in Figure 5. As the can turret rotates, the cams 95, 95' release the cam following rollers 91, 91' and the can engaging heads 97, 97' on the spindles move inwardly and support the cans for free rotation, out of contact with the pockets 76, 76'. As the cans so supported in the chucks approach the periphery of the printing blankets 15, 16, upon continued rotation of the can turret, the forward end of one blanket comes into rolling contact with a can. Rotation is imparted to the cans successively by the tracks 110, 111, 110', 111' carried by the transfer drum. The transfer blanket makes rolling contact with each can as the same revolves with the can turret. The cradles 68, 68' moves radially inwardly relative to the can turret, during the printing operation.

As the cans approach the brackets 21, carried by the outfeed chain 22, the heads 97, 97' are withdrawn from engagement with the cans, by the action of the cams 95, 95', whereupon the cans drop into the brackets 21, by which they are delivered from the machine.

During the continued rotation of the transfer cylinder, the blankets 15, 16 successively engage

the plate rolls 155 of the printing assemblies 17—20, whereby the blankets are re-inked. The plate rolls, in turn, continually receive fresh supplies of ink from the associated form rolls 175, ink cylinders 167, ductor rolls 170, and fountain rolls 168, the ink on the ink cylinders 167 being evenly distributed by the reciprocating distributor rolls 185, 186.

As pointed out above, there are twelve can-supporting chucks on the turret and two transfer blankets on the transfer cylinder. Hence the latter rotates six times as fast as the former. Of course, the invention is not limited to this particular number and speed ratio, since the same principle of operation will be employed whenever the transfer cylinder rotates as many times faster than the can-holding turret as the number of chucks on the turret, divided by the number of blankets on the transfer cylinder.

The operation of the second modification of apparatus is the same as in the preferred form, the principal differences being in the specific means for reciprocating the can end engaging members, rotating the fountain rolls and oscillating the ductor rolls.

The operation of the third modification differs from the first in that continuous coats or bands are applied to the cans in a plurality of layers, as a result of the continuous cylindrical surface on the transfer roll and the fact that the cans make a plurality of rotations in rolling contact therewith.

Although the invention has been described with considerable particularity in this specification, it must be understood that this description and the accompanying drawings are illustrative only and are not restrictive of the invention, as many modifications and variations will readily occur to one skilled in the art. All such changes as are included in the accompanying claims and their equivalents are comprehended by the invention.

We claim:

1. A machine for printing the surfaces of cylindrical articles comprising a revolvable turret, a plurality of rotatable article-supporting chucks mounted on the turret for rotation about their own axes and for radial movement relative to the axis of revolution of the turret, resilient means for urging the chucks radially outwardly, a second rotatable turret, a transfer blanket arranged peripherally thereon, means for continuously revolving both of said turrets to bring the articles supported by the chucks into rolling contact with said blanket for printing, while the chucks and the articles move radially relative to the axis of their supporting turret, and means for limiting the pressure of the articles against the blanket under the influence of said resilient means.

2. A machine for printing the surfaces of cylindrical articles comprising a revolvable turret, a plurality of rotatable article-supporting chucks mounted on the turret for rotation about their own axes and for radial movement relative to the axis of revolution of the turret, a second rotatable turret, a transfer blanket arranged peripherally thereon, means for continuously rotating said turrets in the same direction but with the peripheral speed of the second turret exceeding that of the first, said chucks being positioned relative to the path of revolution of the blanket so that the surfaces of the articles follow that path as the blanket makes rolling contact therewith to print said surfaces and means independent of the

surface contact between the articles and the blanket for rotating the chucks and the articles when in such contact.

3. A machine for printing the surfaces of cylindrical articles comprising means for conveying a line of articles along a predetermined path, resiliently mounted means for supporting the articles for rotation about their axes during at least a portion of their movement, a transfer blanket mounted for movement along a predetermined path coinciding for a predetermined, finite distance with the path of movement of the articles, means for moving the blanket along said path at a speed in excess of the speed of movement of the articles, whereby the blanket contacts the surfaces of articles and makes rolling contact therewith to print said surfaces, means independent of the surface contact between the articles and the blanket for rotating the article supporting means and the articles supported thereby, while the articles are in contact with the blanket, and means in the path of movement of said blanket for applying a printed design to the blanket to be transferred to the articles.

4. A machine for printing cylindrical containers or the like, comprising a rotatable turret having a plurality of radial slideways thereon, rotatable article-supporting chucks mounted for sliding movement on the ways, resilient means for urging the chucks outwardly, a rotatable drum, a transfer blanket supported thereon, means for continuously rotating the turret and the drum to move the containers and the blanket along intersecting arcuate paths, and cooperating means carried by the drum and the chucks for moving the chucks inwardly relative to the turret against the force of said resilient means, to cause the containers to follow the arc of movement of the blanket while making rolling contact therewith.

5. In an apparatus for printing the cylindrical surfaces of cans or the like, a rotatable turret having surfaces forming a plurality of peripheral can-receiving pockets, radial slideways at opposite ends of the pockets, and can-holding chuck assemblies mounted in the slideways for limited radial movement with respect to the turret, said chuck assemblies each comprising a pair of rotatable elements mounted for axial movement to grip the opposite ends of a can in the associated pocket and to support the same out of contact with the pocket for free rotation, and cam following means for moving said elements into and out of engagement with a can.

6. In an apparatus for printing the cylindrical surfaces of cans or the like, a rotatable turret comprising spaced radial heads, a plurality of aligned pairs of can end engaging assemblies carried by the heads, each comprising a bracket mounted for limited radial movement thereon, a can end engaging member journaled for rotation in the bracket and mounted for longitudinal movement, resilient means urging the member toward the can, means for imparting rotation to the member, and cam following means for moving the member away from the can against the force of said resilient means, to release the can.

7. In an apparatus for printing the surfaces of cylindrical cans or the like, a can-holding turret, chuck assemblies yieldingly carried thereby for radial displacement with respect thereto for supporting the cans for rotation about their axes, and driving means for radially displacing and rotating the assemblies, said assemblies comprising

rotatable means for engaging one end of a can, a longitudinally movable and rotatably mounted member aligned therewith, and means for moving the same into engagement with the other end of the can, whereby the can is rotatably supported by its ends between said members, the last-mentioned member having a pair of axially spaced cylindrical surfaces associated therewith on opposite sides of its rotatable support, said cylindrical surfaces being substantially equal in radius to the can radius, whereby said can may be rotated at substantially the same peripheral speed as said cylindrical surfaces when the latter make rolling contact with said driving means.

8. An apparatus for printing the cylindrical surfaces of cans or the like, comprising a transfer cylinder, means for continuously rotating the same, transfer blanket means on the periphery thereof, a turret, means for rotating the same continuously on an axis parallel to the cylinder axis, a plurality of rotatable can-holding chucks mounted for radial movement on the turret, resilient means urging the chucks radially outwardly, and a cylindrical driving surface carried by the transfer cylinder and equal in radius to the surface of the blanket means, each of said chucks comprising a pair of axially aligned rotatably mounted can end engaging elements having associated therewith cylindrical surfaces equal in radius to the cans and positioned to engage the driving surface on the transfer cylinder as the turret rotates, whereby the cans follow the path of movement of the blanket and the blanket and the cans are rotated at the same peripheral speed.

9. An apparatus for printing the cylindrical surfaces of cans or the like, comprising a transfer cylinder, transfer blanket means on the periphery thereof, a turret, a plurality of rotatable can-holding chucks yieldingly mounted on the turret, and a driving surface carried by the transfer cylinder for rotating the chucks, said surface being equal in radius to the surface of the blanket, said chucks each comprising a pair of rotatably mounted, longitudinally movable can end engaging elements, resilient means for urging the elements into position to clamp the can therebetween for rotation therewith, means for continuously rotating the transfer cylinder and the turret, and stationary cam means for moving the elements in the opposite direction to release the cans, said elements each having associated therewith a cylindrical surface equal in radius to the surfaces of the cans and positioned to be engaged by the driving surface on the transfer cylinder and to have contact therewith throughout an appreciable arc of rotation of the turret as the chuck and turret rotate, whereby the cans and the blanket are rotated at the same peripheral speed.

10. In combination, a can-holding chuck assembly and a turret in a can printing machine, said assembly comprising a pair of brackets mounted for limited radial movement in the turret, resilient means urging the brackets radially outwardly, bearing means associated with the brackets, longitudinally movable, rotatable spindles having can end engaging members at their ends mounted in the bearings, means for moving said members into engagement with a can to clamp the same therebetween, and means associated with said members to receive rotation by rolling contact with a driving element while the brackets are moved radially inwardly thereby.

11. In combination, a can-holding chuck assembly and a turret in a can printing machine, said assembly comprising a pair of brackets mounted for limited radial movement in the turret, resilient means urging the brackets outwardly, flanges forming pockets adapted to receive the cans, bearing means associated with the brackets, longitudinally movable, rotatable spindles having can end engaging members at their ends mounted in the bearings, means moving said members into engagement with a can in the pocket to lift the same from said flanges, and means associated with said members to receive rotation by rolling contact with a driving element, thereby to rotate the cans.

12. An apparatus for printing a continuous coating in a plurality of layers upon the surfaces of cylindrical articles, comprising a transfer drum having a cylindrical transfer surface, a turret, radially movable article holding chucks rotatably mounted on the turret for revolution therewith along a path intersecting the drum surface, means for continuously rotating the drum and the turret at such relative speeds as to cause the surfaces of the articles to contact the transfer surface and make a plurality of rotations in rolling contact therewith, and an inking assembly having a plate roll in contact with the transfer surface, whereby ink applied thereto is transferred to the surfaces of the articles in a plurality of layers.

13. An apparatus for printing a plurality of circumferentially continuous bands of different colors upon the surfaces of cylindrical articles, comprising a transfer drum having a cylindrical transfer surface, a turret, radially movable article holding chucks rotatably mounted on the turret for revolution therewith along a path intersecting the drum surface, means for continuously rotating the drum and the turret at such relative speeds as to cause the surfaces of the articles to contact the transfer surface and make a plurality of rotations in rolling contact therewith, and a plurality of inking assemblies having plate rolls in contact with the transfer surface of the drum, said rolls having surfaces arranged to apply continuous bands of differently colored ink to the transfer surface, for transfer to the surfaces of the articles.

14. An apparatus for printing the cylindrical surfaces of containers and the like, comprising a transfer blanket, means for continuously revolving the same about a fixed axis, means for supporting a plurality of containers for rotation about their axes, means for continuously revolving the supporting means along a path intersecting the path of revolution of the blanket, the supporting means being capable of deviation from their line of movement to follow the path of the blanket through an arc of appreciable length, resilient means for urging the containers into contact with said blanket when travelling along said arc, and friction driving means for the container supporting means for rotating the containers and for establishing rolling contact between the containers and the blanket and for limiting the pressure of the containers against the blanket under the influence of said resilient means.

15. A machine for printing the surfaces of cylindrical articles comprising means for supporting the articles for rotation about their axes and for revolution on a circular path, said means being mounted for deviation from the said path, a transfer blanket supported for revolution along a path meeting the path of revolution of the ar-

ticles on an intersecting arc, means for continuously revolving the article-supporting means to bring the surfaces of the articles successively into the path of movement of the blanket, thereby to cause the article-supporting means to deviate from said circular path and to cause the surfaces of the articles to follow the path of revolution of the blanket, means for continuously revolving the blanket while the surfaces of the articles are mov-

ing in contact therewith, and means independent of the surface contact between the articles and the blanket for rotating the article-supporting means and the articles, thereby to cause the cylindrical surfaces of the articles to make rolling contact with the blanket.
